UNITED STATES PATENT OFFICE.

WILLIAM H. FERGUSON, OF COLUMBUS, OHIO.

SPARKER FOR EXPLOSIVE-ENGINES.

1,152,085.

Specification of Letters Patent. Patented Aug. 31, 1915.

Application filed March 12, 1915. Serial No. 13,836.

To all whom it may concern:

Be it known that I, WILLIAM H. FERGUSON, a citizen of the United States, residing at Columbus, in the county of Franklin and State of Ohio, have invented a certain new and useful Improvement in Sparkers for Explosive-Engines, of which the following is a specification.

This invention relates to an electric circuit making and breaking device for use in connection with internal combustion engines, and has for its principal object to provide improved means whereby the duration of the contact in such devices is abbreviated and the leaving of the contacts closed made impracticable so as to avoid waste of electrical energy.

A further object of the invention is a construction in which contact is made only when the motor turns in the proper or normal direction.

The invention is embodied in the example herein shown and described, the features of novelty being pointed out in the claims.

In the accompanying drawing, Figure 1 is a plan view showing the parts approaching the sparking position, the contacts being out of contact. Fig. 2 shows a similar view without the insulating plate but showing the contacts in contact. Fig. 3 is a section on the line $x-x$ Fig. 1.

In the views 5 designates an insulating plate and 6 the motor shaft which is rotated by the engine, as usual. 7 is a disk keyed 35 to the shaft 6 and having projecting from its rim several noses 8 with inclined cam edges. These noses correspond in number to the number of cylinders to be fired.

Mounted on the shaft 6 adjacent the disk 40 7 is another disk 9 having cam noses 10 corresponding in number to the noses 8. One edge of each of the noses 10 is inclined and the other straight or radial to the axis of the shaft. The disk 9 is loose on the shaft 45 but is attached thereto by a spring 11 which tends yieldingly to hold the disk 9 with the noses 10 and 8 out of register with each other and the noses 10 in advance of the noses 8.

50 Fulerumed on a pin 12 on the plate 5 is a lever 13 carrying at one end an adjustable contact 14 suitably electrically insulated from the lever by insulating material 15 and at the other end with a cam projection 16. The projection 16 lies in the path of movement of the noses 10 only. A spring

25 secured on the plate 5 bears upon that arm of the lever 13, which carries the projection 16, in a manner tending to hold the contact 14 outward. An adjustable stop 26 60 is provided on the plate 5 to limit the outward position of the contact 14 due to the pressure of the spring 25. In the construction shown the termini of the said lever 13 reach to substantially diametrically opposite sides of the disks 7 and 9.

17 is a stop arm pivotally mounted on a pin 18 on the plate 5; and connecting said arms 17 and the plate 6 is a coil spring 19 tending to draw the free end of said arm 70 17 toward the rim of the disks 7 and 9. The stop arm 17 is provided at its said free end with a head 20 broad enough to intercept the noses 8 and 10 of both disks 7 and 9. Said arm 17 carries a contact 21, said contact 75 being preferably mounted upon a spring 22 attached to the arm 17 so as to be slightly yielding. The outward oscillation and the normal position of the contact 21 on the arm 17 is limited and determined by a stop extension 17^a of the arm 17.

In the construction, as shown, the direction of normal rotation of the shaft 6 is indicated by the arrows. When the shaft 6 is thus rotated the head 20 positively intercepts the nose 10 and increasingly places the spring 11 under tension. Upon continued rotation of said shaft 6 the head 20 comes into contact with an inclined edge of the nose 8 and is by said edge raised beyond the 90

nose 10 thereby permitting the disk 9 under the tension of the spring 11 to be thrown in advance of the disk 7. This throw of the disk 9 brings another of the noses 10 forcibly into contact with and past the cam projection 16 of the lever 13 throwing the corresponding end of that lever outward and the contact 14 inward into electrical contact with the at-that-time raised contact 21. The inward throw of the contact 14 is quick 95 or momentary, and said contact of the contact 14 with the contact 21 only takes place while the head 20 of arm 17 is resting upon the crown of a nose 8. The duration of the contact is controlled by the form of the nose 10 and projection 16 and the speed with which that nose is thrown under said projection 16. Further rotation of the shaft 6 from the position shown in Fig. 2 permits the head 20 to drop off the nose 8 thereby 100 carrying the contact 21 inward into position to engage the next approaching nose 10,

105 55 110

Any reverse rotation or rockings of the shaft 6 cannot produce a contact of the contacts 21 and 14 because the noses 8 and 10 are normally held out of register and cannot be 5 brought into effective register because of a stop pin 23 on the disk 7, said stop pin preventing rotation of the disk 9 in a reverse direction prior to any registration of the noses 8 and 10 if the shaft happens to rotate 10 or rock in that direction. When rocking or rotating in reverse direction the inclined edges of the noses slip under the inclined inner surface of the head 20 and while they throw the stop arm 17 and contact 21 outward they do not at the same instant operate 15 the lever 18 to throw the contact 14 inward. It follows, therefore, that the contacts 21 and 14 are never left electrically connected or in such a way as to permit waste of the 20 electrical energy.

The electrical energy can be brought from a suitable source to the contact 14 through a wire 27 and grounded in the machine through the other contact as shown and as 25 well understood or in any other suitable manner.

What I claim is:

1. An electrical sparking device for explosive engines comprising, in combination, 30 a pair of movable contacts, a member for moving one of said contacts to sparking position and a tension member movable relatively to first mentioned moving member for bringing the other contact to sparking position.

2. An electrical sparking device for explosive engines comprising, in combination, a pair of yieldingly held movable contacts, a member for moving one of said contacts to 40 sparking position and tension member movable relatively to the first mentioned moving member for bringing the other contact to sparking position.

3. An electrical sparking device for explosive engines comprising, in combination, 45 a pair of contacts, a rotary member for moving one of said contacts to sparking position and a tension member actuated by the rotary member for moving the other contact to sparking position.

4. An electrical sparking device for explosive engines comprising, in combination, a pair of contacts, a rotary member for moving one of said contacts to sparking position 55 and a tension member carried by the rotary member for moving the other contact to sparking position.

5. An electrical sparking device for explo-

sive engines comprising, in combination, a pair of contacts, a rotary member for actuating one of said contacts to move it to sparking position, and a spring actuated member carried by the rotary member for moving the other contact into sparking position.

6. An electrical sparking device for explosive engines comprising, in combination, a pair of contacts, a rotary member for moving one of said contacts to sparking position, a tension member actuated by the rotary member for moving the other contact to sparking position and means for intermittently placing said tension member under tension and releasing the same to impart movement to the tension member independent of the rotary member.

7. An electrical sparking device for explosive engines comprising, in combination, a pair of contacts and carriers for the same, a rotary member for moving one of said carriers to place its contact in sparking position, a tension member actuated by the rotary member for moving the other carrier to place its contact in sparking position, the carrier for the last named contact being 85 adapted to place said tension member under tension and release the same to impart movement to said tension member independent of the rotary member.

8. An electrical sparking device for explosive engines comprising, in combination, a contact, a rotary member for intermittently moving said contact to sparking position, a second contact and a second rotary member movable independently of the first mentioned rotary member to move that contact into 95 sparking position.

9. An electrical sparking device for explosive engines comprising in combination, a pair of movable contacts, a lever carrying 100 one of said contacts and an arm carrying the other, a rotary member having a plurality of projections for intermittently moving the contact of the arm to sparking position and a second rotary member having a plurality of projections and having a resilient device connecting said rotary member with the first mentioned rotary member and means for intermittently placing said resilient connecting device under tension to actuate 105 said lever to move its sparking device to sparking position.

WILLIAM H. FERGUSON.
